UNITED STATES PATENT OFFICE.

GEORGE HENRY HAWKINS EMETT, OF NEW WESTMINSTER, CANADA,
ASSIGNOR TO PIERRE BARNES, OF SEATTLE, WASHINGTON.

T-SQUARE-CLAMPING DEVICE.

SPECIFICATION forming part of Letters Patent No. 737,090, dated August 25, 1903.

Application filed April 28, 1902, Serial No. 104,927. (No model.)

To all whom it may concern:

Be it known that I, GEORGE HENRY HAWKINS EMETT, a subject of the King of England, residing at New Westminster, in the Province 5 of British Columbia and Dominion of Canada, have invented certain new and useful Improvements in T-Square-Clamping Devices, of which the following is a specification, reference being had therein to the accompanying drawings.

This invention relates to drafting instruments, and particularly to clamps for T-squares.

The object of the invention is to provide a 15 holder or clamp of this class which will be simple, inexpensive, and easy of adjustment and which will securely hold a T-square to any set position transversely of the drawing-board. This object is attained by the device 20 or devices hereinafter fully described and which is illustrated in the accompanying drawings, in which—

Figure 1 is a plan view of a T-square secured to a set position on a drawing-board by 25 my invention. Fig. 2 is a front elevation thereof. Figs. 3 and 4 are respectively perspective views of the blade attachment A and clamp C, shown in the other views.

The blade attachment A consists of a plate 30 adapted to lie flat upon the outer end of the T-square blade B and is provided with a tongue t, depressed below its under surface for hooking or engaging in the hole h, commonly made in the square-blade in proximity 35 to its end. The clamp C is formed of a plate p, having a bend or flange f at right angles to the plate-body and provided with a threaded aperture d, through which is passed a clamping-screw s, registering therewith. At 40 one end of the said screw is a milled head e, integral with the screw, and loosely secured to the other end by riveting is a washer w. Holes g and g' are provided, respectively, in

the clamp and attachment for connecting the said parts by a wire i, which is preferably 45 sunk into grooves k so that it will be flush or even with the surfaces thereof.

The clamp and attachment aforesaid are preferably made of metal; but any other suitable material may be used instead. 50

The operation and advantages of the device are obvious from the above description. It may be mentioned, however, that it may be applied to T-squares of varying lengths used upon a drawing-board by simply changing the 55 wire. Also by putting a tension through the T-square blade upon the stock the latter bears firmly against the edge of the board and presents a right angle thereto. Further, it is capable of carrying a triangle or protractor the 60 entire length of the blade and permits greater freedom of movement to the draftsman in the use of both hands to his work. He can, for instance, work on either side of a triangle, as the light or other circumstances may render 65 desirable, and in plotting the vernier of the protractor may be adjusted with one hand and the markings made coincidently with the other.

Having thus described my invention, what 70 I claim as new, and desire to secure by Letters Patent, is—

The herein-described device, comprising a T-square-blade attachment having a projection therebeneath for engaging with the hole 75 in the said blade end, a clamp formed of a plate having a bend therein and a screw passed through a threaded aperture thereof; and connection between the said attachment and the clamp, substantially as set forth. 80

In testimony whereof I affix my signature in presence of two witnesses.

GEORGE HENRY HAWKINS EMETT.
